CLAIM

We claim the ornamental design for lanyard slider, as shown and described.

DESCRIPTION

FIG. 1 is a front, left perspective view of a lanyard slider showing our new design.

FIG. 2 is a top plan view thereof.

FIG. 3 is a bottom plan view thereof.

FIG. 4 is a front plan view thereof.

FIG. 5 is a rear plan view thereof;

FIG. 6 is a left side plan view thereof; and,

FIG. 7 is right side plan view thereof.
